(57) **CLAIM**

I claim the ornamental design for a protective cover for second stage regulator of scuba gear, as shown and described.

DESCRIPTION

FIG. 1 is a perspective view of a protective cover for second stage regulator of scuba gear showing my new design in an opened configuration;

FIG. 2 is a side elevational view showing my new design in a closed configuration, the elevational view of the opposing side being a mirror image thereof;

FIG. 3 is a front elevational view showing my new design in a closed configuration;

FIG. 4 is a rear elevational view showing my new design in a closed configuration;

FIG. 5 is a top plan view thereof;

FIG. 6 is a bottom plan view thereof; and,

FIG. 7 is a reduced perspective view showing the protective cover for second stage regulator of scuba gear in an opened configuration; the broken lines depict environmental structure for illustrative purposes only and form no part of the claimed design.
